MARIE A. BLOOMFIELD, OF NEW YORK, AND HERBERT E. HAWES, OF BROOKLYN, NEW YORK, ASSIGNEES OF ONE-THIRD TO WALTER D. EDMONDS, OF NEW YORK, N. Y.

MARKING ATTACHMENT FOR SEWING-MACHINES.

SPECIFICATION forming part of Letters Patent No. 718,080, dated January 18, 1903.

Application filed August 18, 1898. Serial No. 688,868. (No model.)

To all whom it may concern:

Be it known that we, MARIE A. BLOOMFIELD, of the borough of Manhattan, and HERBERT E. HAWES, of the borough of Brooklyn, 5 in the city and State of New York, citizens of the United States, have jointly invented certain new and useful Improvements in Marking Attachments for Sewing-Machines, of which the following is a specification, reference being had to the accompanying drawings, in which—

Figure 1 is a side view of our invention, certain of the parts being illustrated in dotted lines because of their position behind other 15 parts from the point of view of the observer. Fig. 2 is a top view of certain parts of our said invention, and Figs. 3, 4, and 5 are views of details.

The object of our invention is to produce a 20 marking mechanism or attachment to the ordinary sewing-machine which shall be simple and effective in its construction and will enable the operator on the machine to automatically mark on the goods continuous lines in 25 desired places which shall serve as guides for subsequent treatment or sewing of the goods—as, for instance, in sewing so-called "tucks" to 30 mark continuously the goods and parallel with the line of the seam while the same are being sewed, so as to designate on the goods the location of the next fold required to be made in order to sew the next tuck; and it is also the 35 object of our invention to effect such marking as aforesaid without the exertion of other power or attention on the part of the operator than heretofore during the progress of the sewing.

In the drawings, A represents the presser-bar of the ordinary and well-known type of 40 sewing-machine, to which we secure by set screw a, operating in a yoke or sleeve b, the supporting-sleeve B. In the supporting-sleeve B turns the shaft C, having fixed thereto on one side of said sleeve the ratchet-wheel D 45 and on the other side the gear-wheel E, adjoining and outside of which and sleeved upon the shaft C is the actuating-link F, within which turns the shaft c', carrying fixed thereto at its inner end the gear-wheel d, meshing 50 with the gear-wheel E and also turning in said

link, and at the farther extremity thereof the shaft e, having fixed thereto the gear-wheel G, which meshes with the said gear-wheel d, the continuation of said last-mentioned shaft passing between the needle N and the said 55 presser-bar A, and preferably graduated and carrying the sleeved marker-wheel and its supporting parts, as hereinafter described.

To the needle-bar H of the machine one end of the connecting-link I is pivotally secured in any convenient manner, as by the adjustable and removable clamp h, through which is threaded the set-screw h', which bears upon the needle-bar H, and thus causes the clamp h to engage and draw against the 60 binding-plate h². (See Fig. 3.) The other end of said link I is pivotally connected, as at J, with another link I', which latter at its opposite extremity is journaled upon the said shaft C and provided with a pawl P, engaging 65 in the teeth of the ratchet-wheel D.

W is a circular marker-wheel, preferably constructed of chalk or other material sufficiently soft to be abraded by friction against the goods. The said wheel is mounted upon 70 the exteriorly-threaded sleeve K, having the flange or head k and upon which rides the flange k'. The marker-wheel disk is centrally bored out, so as to admit of its being passed over the threaded sleeve K and so as 75 to bear against the flange k. The follower or washer flange k' is likewise bored out and placed in position, as shown, next to and on the outside of the marker-wheel. A milled nut L, internally threaded to correspond with 80 the screw of K, is then screwed down upon the latter, thus firmly clamping the marker-wheel in position, which, with its thus connected parts, will now slide up and down the shaft e to the desired location, as indicated 85 by the graduated scale thereon, and there it may be firmly fixed by turning the set-screw M.

O is a spring one extremity of which is fixed to and bears upon the supporting-sleeve B and the other upon the actuating-link F, 90 so as to depress the latter, with the marker-wheel, and thus insure sufficiently forcible bearing by the latter against the goods.

The operation of my invention is as follows: The presser-bar A is inserted in the 95

sleeve *b* and the latter firmly fixed upon the former by screwing down the set-screw *a* at such a point as to insure a moderate pressure upon the goods by the marker-wheel *W*. The movable clamp *h* and binding-plate *h'* are next placed in position at such a point on the needle-bar *H* as to insure proper action by the pawl *P*, as hereinafter described. The spring *O* is next adjusted so as to operate with such sufficient force upon the marker-wheel as to insure its constant pressure upon the goods, and thus compensate for its diminishing diameter due to wear against the goods. The goods being sewed are fed in the direction of the arrow *P'*. The reciprocating movement of the needle-bar *H* communicates such motion to the pawl *P* as to cause it to operate upon the ratchet-wheel *D*, and thus rotate the shaft *C* with its gear-wheel *E*, the latter meshing with the gear-wheel *d*, which in turn causes the gear-wheel *G* and its shaft *e*, carrying the marker *W*, to rotate in a direction opposite to that in which the goods are being fed, and thus the marker is caused to intermittently brush positively against the goods, and thus mark them plainly while they are held by the needles passing through them.

By means of the set-screw *M*, gage *e*, and other parts entering into the mounting of the marker-wheel *W*, as heretofore stated, the latter may be moved readily and set at substantially any required distance from the seam which is being sewed. By this means and without in any way interfering with the usual operation of the machine and its parts the goods may be simultaneously with the sewing automatically marked parallel with and at any usually required distance from the seam, and thus the labor of separately preparing and marking the goods for the next tuck in tucking, for instance, is greatly diminished, the mark-line produced by our device, as aforesaid, affording in such a case a guide or location of the line along which the material is to be folded in making the next tuck. In certain kinds of sewing it may be more desirable to rotate the marker in the same direction as the feed of the goods, and this may be readily accomplished by inserting another geared wheel in the train carried by the actuating-link *F*.

What we claim as new, and desire to secure by Letters Patent, is—

1. In combination with a sewing-machine mechanism a marker-wheel of abradable material and means for intermittently rotating the same while the needle is in the goods.
2. In combination with a sewing-machine mechanism an abradable rotatory marker-

wheel *W* intermittently rotating while the needle is in the goods and mechanism connecting the reciprocating needle-bar with the said wheel for the purpose of rotating the latter.

3. The combination of a sewing-machine with an abradable rotatory marker-wheel rotating intermittently while the needle is in the goods and carried at one extremity of a link *F* the opposite extremity of which is carried on a yoke *b* supported on the presser-bar *A* and mechanism connecting the marker-wheel with the reciprocating needle-bar to cause said marker-wheel to rotate as aforesaid.

4. In combination with a sewing-machine mechanism, a rotatory marker-wheel rotating intermittently while the needle is in the goods, the link *F*, shaft *e*, and gear-wheels *G*, *D*; *E*, shafts *C'*, *C*, ratchet-wheel *D*, connecting-links *I* and *I'*, spring *O*, spring-pawl *P*, yoke or sleeve *B*, set-screw *A*. 80

5. In combination with a sewing-machine mechanism, a rotatory marker-wheel rotating intermittently while the needle is in the goods, the link *F*, shaft *e*, and gear-wheels *G*, *D*, *E*, shafts *c'*, *C*, ratchet-wheel *D*, connecting-links *I* and *I'*, spring *O* spring-pawl *P*, yoke or sleeve *B*, set-screw *A*, removable clamp *h*, and set-screw *h'*. 85

6. In combination with a sewing-machine mechanism, a rotatory marker-wheel rotating intermittently while the needle is in the goods, the link *F*, shaft *e*, and gear-wheels *G*, *D*, *E*, shafts *C'*, *C*, ratchet-wheel *D*, connecting-links *I* and *I'*, spring *O* spring-pawl *P*, yoke or sleeve *B*, set-screw *A*, removable clamp *h*, and set-screw *h'*, flanges *k*, *k'*, milled nut *L*, washer or flange *k'* and set-screw *M*. 95

7. In combination with a sewing-machine mechanism a rotary marker-wheel *W* in combination with a flange *k*, threaded sleeve *K*, flange *k'*, milled nut *L*, set-screw *M*, needle-bar *H*, shaft *e* and mechanism operatively connecting said needle-bar with said shaft. 100

8. In combination with a sewing-machine mechanism a positively-rotated marker-wheel of abradable material and means to actuate and connect the same operatively with the needle-bar. 105

9. In combination with a sewing-machine mechanism a positively-rotated marker-wheel of abradable material yieldingly held against the goods, and means for actuating the same. 110
